UNITED STATES PATENT OFFICE.

RALPH G. JOHNSON, OF PITTSBURGH, PENNSYLVANIA.

METHOD FOR SEALING SHAFTS, TUNNELS, AND THE LIKE.

1,065,369.

Specification of Letters Patent. Patented June 24, 1913.

Application filed November 14, 1912. Serial No. 731,404.

To all whom it may concern:

Be it known that I, RALPH G. JOHNSON, a citizen of the United States, residing at Pittsburgh, in the county of Allegheny, State of Pennsylvania, have invented certain new and useful Improvements in Methods for Sealing Shafts, Tunnels, and the Like; and I do hereby declare the following to be a full, clear, and exact description of the invention, such as will enable others skilled in the art to which it appertains to make and use the same.

This invention relates to the construction of shafts, tunnels and other excavations and has particular application to an improved method of lining and sealing the shaft whereby the inflow of water to the latter from the surrounding rock or ground is effectively prevented.

It is well known to engineers, contractors and others skilled in the art considerable difficulty is usually experienced in rendering timber and metal lined shafts and tunnels water proof, in the sense of preventing the flow of water into the shaft from the fissures and crevices formed in the rock or bed in which the shaft is sunk. By the employment of my improved method, not only is such a shaft positively sealed against the entrance of water, but a strong, durable and permanent lining for the shaft is provided. A further advantage incident to my method is that not only is the shaft maintained comparatively dry, but the necessity and expense incident to resorting to the use of a pump for emptying the water from the bottom of the shaft is avoided.

With the above recited objects and others of a similar nature in view, my invention consists in the improved method set forth in and falling within the scope of the appended claims.

In the accompanying drawings: Figure 1 is a horizontal sectional view of a shaft constructed in accordance with my invention. Fig. 2 is a vertical sectional view thereof.

In the present instance I have shown and described my invention as employed in connection with a timber lined shaft, as the vast majority of mine shafts at the present time are of this nature. I wish it to be understood, however, that I do not limit my invention to its employment in this particular connection.

Referring now to the accompanying drawings in detail, the numeral 1 designates the

rock or ground in which the excavation 2 is made.

The numeral 3 designates any form of ordinary timber lining or lagging, such as 60 planking or the like, while in the present instance timber sets, or rings or frames of timber for the lagging are shown at 4. Of course it is to be understood that the form of timbering shown herein is merely by way 65 of illustration as any form of lining either of timber or metal may be employed.

In the practice of my invention a portion of the timber lining in the section to be water sealed is removed in sections and the 70 rock rib is then cut, if necessary, and leaves a certain clearance behind the timber space. Sheets of corrugated iron or canvas 6 or other suitable material are then placed next to the rock rib to form the drainage channels 75 7. Pipe sections 8 lead from these drainage channels out through the timber lagging into the shaft. Concrete, cement or other suitable material 9 is then placed behind the timber lining or lagging and reinforced, if 80 desired, to withstand whatever pressure of water which may occur at that point. It will thus be seen that at this stage we have a complete concrete wall surrounding the shaft timbering and through which wall project 85 numerous pipes which convey the water from the rock rib into the shaft. When this concrete wall has sufficiently set all of the pipes are plugged or stopped up, with the exception of one or more which are designed 90 to have a concrete grouting machine operating under pressure attached thereto. Thin cement grout preferably made from Portland cement is then forced through these unplugged pipes, shown in the drawings at 95 10, into the water bearing fissures in the rock under air pressure sufficient to overcome the pressure of water flowing through the fissures or crevices. This cement grout will thus fill and seal the crevices and effectively prevent the flow of the water into the shaft.

Thus the shaft is rendered water proof so far as the inflow of the water from the surrounding rock or ground is concerned and the numerous disadvantages incident 105 to the presence of water in the bottom of the shaft are obviated.

While I have herein shown and described one embodiment of my invention, I wish it to be understood that I do not limit myself 110 to all the precise details herein set forth by way of illustration, as modification and va-

riation may be made without departing from the spirit of the claims, for instance, the invention is applicable to shafts of fabricated steel, wrought iron sets and to reinforced concrete sets and lagging.

What is claimed is:

1. The herein described method which consists in providing a lined shaft with a concrete wall back of the lining and forcing sealing material under pressure through passageways formed through the wall to seal the shaft against the entrance of water.
- 10 2. The herein described method which consists in providing a timber lined shaft with a concrete wall back of the lining, forming drainage channels between the wall and the surrounding ground, extending water conducting pipes through the lining and wall into communication with the channels, and forcing a sealing material under pressure

through certain of said pipes to seal the shaft against the entrance of water.

3. The herein described method which consists in providing a timber lined shaft with a concrete wall back of the lining, forming 25 drainage channels between the wall and the surrounding ground, extending water conducting pipes through the lining and wall and into communication with the channels, to draw water into the shaft, then plugging 30 certain of said pipes, and subsequently forcing cement grout through certain other of the pipes to seal the shaft against entrance of water.

In testimony whereof, I affix my signature, in the presence of two witnesses.

RALPH G. JOHNSON.
